UNITED STATES PATENT OFFICE.

HERMAN PLAUT, OF NEW YORK, N. Y.

DESIGN FOR AN ELECTROLIER.

45,019.

Specification for Design.

Patented Dec. 9, 1913.

Application filed September 18, 1913. Serial No. 790,543. Term of patent 7 years.

To all whom it may concern:

Be it known that I, HERMAN PLAUT, a citizen of the United States, and a resident of the borough of Manhattan, city, county, and State of New York, have invented a new, original, and ornamental Design for an Electrolier, of which the following is a specification, reference being had to the accompanying drawing, forming a part hereof, which shows the design in perspective.

The design comprises a substantially cylindrical body ornamented by a draped

scarf hanging from alternately arranged plaques and draped knots, the bottom of the body being curved with radiating flutes, said body being supported by curved arms, from a centrally located top.

I claim:

The ornamental design for an electrolier, substantially as shown and described.

HERMAN PLAUT.
